UNITED STATES PATENT OFFICE.

ARCHIBALD W. PAULL, OF WHEELING, WEST VIRGINIA, ASSIGNOR TO WHEELING STAMPING COMPANY, OF WHEELING, WEST VIRGINIA, A CORPORATION OF WEST VIRGINIA.

DESIGN FOR A PERCOLATOR.

58,818.

Specification for Design.

Patented Aug. 30, 1921.

Application filed March 26, 1921. Serial No. 455,989. Term of patent 14 years.

To all whom it may concern:

Be it known that I, ARCHIBALD W. PAULL, a citizen of the United States, residing at Wheeling, Ohio county, West Virginia, have invented a new, original, and ornamental Design for Percolators, of which the following is a specification, reference being had to the accompanying drawings, forming part thereof.

The drawing is a side view of a percolator embodying the design.

I claim:

The ornamental design for a percolator, as shown.

ARCHIBALD W. PAULL.
